WAX THREAD SEWING MACHINE WITH A LOOPER

Frank E. Cole, Manchester, Mass., assignor to United Shoe Machinery Corporation, Flemington, N.J., a corporation of New Jersey

Original application October 16, 1953, Serial No. 386,551. Divided and this application August 6, 1958, Serial No. 753,547

8 Claims. (Cl. 112—42)

The present invention relates to improvements in a wax thread shoe sewing machine with a looper and is herein disclosed in a preferred form as embodied in an inseam sewing machine having means for waxing the thread and a trimming mechanism for trimming the sewn seam.

The present application is a division of applicant's co-pending application Serial #386,551 filed October 16, 1953 for Shoe Machines.

It is a principal object of the invention to improve the construction and operation of the inseam sewing mechanism of the machine with particular reference to the devices for guiding and waxing the thread.

With this and other objects in view as may hereinafter appear a feature of the invention consists in the means provided for guiding the thread through the machine whereby the thread passing from the take-up of the machine is guided to the work in a more direct path in which protection is afforded to the thread during its passage through the machine substantially to the looper eye. To this end the thread is arranged to be drawn from an idler roller in the machine head through an axial bore in the looper shaft, and through the looper eye. The path followed is substantially a straight line. The arrangement shown is of particular value in a machine of the type described having a trimming mechanism for trimming the sewn seam to protect the thread, and particularly the waxed portion thereof, from direct contact with the air stream produced by the chip exhaust blower, and also to protect the thread from possible contact with the rotary trimming knife.

A feature of the invention consists in the provision of a novel and improved thread waxing device which comprises a container for cold liquid wax, and a conduit system including a return conduit to the wax pot through which wax is continuously forced by a feed pump, in order to prevent clogging of the conduits and to maintain the wax in usable condition. A plunger type of pump is employed which imparts successive surges to the wax through the conduits, timed to cause the pressure to be at a maximum during that portion of the sewing cycle when the thread is moving.

Further in accordance with the invention, the thread waxing device of the illustrated construction is arranged to apply the wax to the thread as it passes through the eye of the looper just prior to the time when the thread is first drawn through the work by the needle in its loop drawing stroke. The wax is supplied to the looper nose through a conduit formed in the looper shaft and connected at its upper end with the wax circulating conduit system above referred to. In addition to the more obvious advantages of handling dry thread in the machine which are obtained by the preferred arrangement shown, the application of wax to the thread in the looper nose has the further advantage that each successive stitch will be finally drawn in and set before the wax hardens, thereby substantially improving the quality of the stitching produced in the machine.

2

The several features of the invention consist also in the devices, combinations and arrangement of parts hereinabove described and claimed which, together with the advantages to be obtained thereby, will be readily understood by one skilled in the art from the following description, taken in connection with the accompanying drawings in which

Fig. 1 is a detail view of the sewing mechanism of the machine looking from the right and partly in section, to illustrate particularly the construction and operation of the mechanism for supplying wax to the thread;

Fig. 2 is a detail view in left side elevation, partly in section, illustrating particularly the supporting and actuating connections for the looper, the thread finger, and needle, and including the conduit for supplying cold wax to the thread at the tip of the looper;

Fig. 3 is an enlarged detail sectional view showing the tip of the looper and the means for waxing the thread mounted therein, and

Fig. 4 is a detail sectional view taken on a line 4—4 of Fig. 2.

Referring to the drawings, the machine disclosed as embodying in a preferred form the several features of the invention is a chainstitch shoe sewing mechanism having a curved hook needle 120 movable in the line of feed, an oscillatory looper 122 and a thread finger 124 which is movable in a direction substantially parallel to the line of feed and away from the trimming knife of the machine, these parts being located entirely at that side of the sewing point away from the completed stitches of the seam to cooperate with a rotary tubular knife 130 which is of relatively large size with its axis parallel to the line of feed and with the cutting edge of the knife passing transversely across the sewn inseam. The illustrated machine is provided with a chip exhaust device which includes a chip collector and exhaust conduit generally indicated at 526 in Figs. 1 and 2, which is adapted to collect and to remove chips taken off by the rotary inseaming trimming knife.

The shoe, mounted on a last and preferably carried on an automatic support, is guided in position with relation to the several operating devices during the transfer of the operation about the sole margin of the shoe by means of a channel guide 138 which is arranged to ride in a stitch receiving channel and support the shoe against the needle, and the cooperating welt guide designated at 140 which yieldingly engages against and is periodically locked against the outer edge of the shoe.

The mechanism for supporting and actuating the sewing instrumentalities of the illustrated machine, while in general similar to corresponding parts illustrated in a United States patent to Morrill Patent No. 2,529,095 dated November 7, 1950, will be briefly described as follows in connection with Figs. 1 and 2 of the drawings.

The curved hook needle 120 together with its supporting segment 554 is carried on an oscillatory feed lever 556 having back and forth movement in the line of feed. The needle feed lever is formed with a sleeve hub which is mounted on a vertical pivot shaft 558 and a rearwardly extending cam lever arm 560 which carries a follower roller 562 for engagement with a peripheral feed cam track in a cam disk on the sewing cam shaft of the machine. The needle 120 is mounted on a segmental support 564 and is further supported against lateral strains by means of a needle guide 566. Oscillatory movements are imparted to the needle segment 554 to cause the needle to pierce and to draw thread through the work by means of connections comprising a link 568 connected at one end to the segment 554 and at its other end to a lever freely mounted to rotate on an axis provided by a transversely extending shaft 572. The lever 570 is

60
65
70

connected by a link 574 to a needle cam actuated lever 575 (Fig. 1).

The looper 122 is supported on a rock shaft 576 to turn on a small radius about an axis inclined forwardly from the vertical and substantially in line with the end of the needle when in the needle threading position. The looper rock shaft 576 is supported for rotational movement in a bore in a forwardly extending bracket 578 carried on the nose of the sewing head. The looper rock shaft 576 is carried by and is fixedly secured with a sleeve shaft 577 mounted to turn on ball bearings in said bore. A clamping nut 580 is provided for fastening together the sleeve shaft 577 and looper rock shaft 576. The sleeve shaft 577 is provided adjacent its lower end with a worm gear 582 which meshes with a worm 584 on a rearwardly extending driving sleeve 586 externally supported in a bearing formed on the bracket 578.

A tapered pinion 588 formed on the rearward end of the driving sleeve 586 meshes with a correspondingly tapered gear segment 590 on one arm of the bell crank lever 592 supported to turn on the sleeve hub on the needle actuating lever 570. An upwardly extending arm of the bell crank 592 is connected by a link 594 with one arm of a cam actuated lever 596.

The thread finger 124 is secured to the forward end of a drive shaft 598 which is mounted within the sleeve drive shaft 586. At its rear end the shaft 598 is formed with a beveled gear segment 600 meshing with a beveled gear segment 602 which constitutes one arm of a bell crank 603 mounted to turn on the sleeve hub of the needle actuating lever 570. The other arm of the bell crank 603 is connected by a link 604 with a cam actuated lever indicated at 606.

The thread handling devices of the machine include additionally a thread take-up and a thread tensioning device. The thread take-up comprises a take-up lever 610 (see Fig. 1) which is supported intermediate its length to turn on a pivot 612. At its forward end lever 610 carries a take-up roller 614, and at its rear end is provided with a cam follower roller 616.

The thread, drawn from a suitable source of supply, passes around a tension wheel 618 of conventional design, under a roller 620, over a take-up roller 614, around rollers 622 and 624, and thence downwardly to the looper 122.

In the illustrated machine the thread is arranged to pass downwardly through a central bore in the looper rock shaft 576 so that the thread is drawn through the work by the take-up roller 614 and idler pulleys 622 and 624 during the take-up in a direction which forms a substantially straight-line extension of the perforation through the work. In the illustrated machine, this arrangement for guiding the thread has the further advantage that the thread passing through the bore in the looper rock shaft 576 is protected from the air stream created by the chip exhaust blower until it reaches a point close to the looper eye.

Further in accordance with the invention a novel and improved thread waxing device is provided which is particularly adapted for applying cold wax to the thread just prior to the point at which the newly waxed thread will first be drawn into the work by the needle upon its loop drawing stroke. The thread waxing mechanism of the illustrated machine comprises a wax pot 700 which is mounted on the side of the machine and serves as a reservoir for a supply of cold liquid wax. There is provided in the bottom of the wax pot an outlet in the form of a depending cup 702 (Fig. 1) to which is connected a conduit or tube 704 through which liquid wax is conveyed to a chamber 706 (Fig. 2) formed within a block 708 fitted over the upper end of the rotatable looper supporting rock shaft 576. The chamber 706 is closed at its upper and lower ends by bearing washers 710, 712 which are externally supported on the block 708 and provide an oil-tight fit with the rotatable looper rock shaft 576. A second conduit 714 (Fig. 1) connected be-

tween the chamber 706 in block 708 and an inlet port 716 in the under side of the wax pot 700 serves as a return channel for wax which thus is permitted to circulate from the outlet designated at 702 through conduit 704 into the chamber 706 and thence through conduit 714 and inlet port 716 back to the wax pot.

Wax is forced through the connections above-described by means of a pump comprising a cylindrical chamber 718 (Fig. 1) provided by an upward extension of the cup 702 and a piston 720 supported to slide in the chamber. The piston 720 is connected by a connecting rod 722 with one arm of a lever 724, the other arm of which is connected to an eccentric link 726 and strap 728 which is mounted on an eccentric 730 on the cam sewing shaft 196 of the sewing machine. Wax is drawn into the pump chamber during the upward movement of the piston 720 through a port 732 past a check valve comprising a spring-seated ball 734, and is thereafter forced outwardly through the outlet 702 and conduit 704 through a second check valve provided by a ball 736 spring seated in the cup 702. Excess wax forced through the chamber 706 is returned through conduit 714 and inlet 716 past a check valve provided by another spring-seated ball element 738. The pulsations provided by the eccentric pump above described are preferably timed with relation to the sewing cycle to increase the wax pressure when the thread is running, beginning as the looping is started and ending with the needle in its fully retracted position.

The circulatory system for supplying wax to the machine as above described has the particular advantage that any tendency of the wax to clog or harden in the relatively small conduits is overcome and the wax in the wax pot 700 is at all times sufficiently stirred and agitated to prevent deterioration.

Further in accordance with the invention, the wax supplied by the pressure system above described is adapted to be applied to the thread at the point where it passes through the nose of the looper so that the waxing of the thread takes place at the last possible moment before the thread is drawn into the work. To this end the looper rock shaft 576 is formed with a conduit which extends downwardly along the length of the looper rock shaft 576 eccentric to the axis and terminates at its lower end in a wax applying chamber 742 extending substantially the length of the looper nose. The conduit 740 may be formed by cutting a slot longitudinally in the periphery of the looper rock shaft 576, the slot being closed by a cover member 743 as shown in Figs. 2 and 4. Stripper rings 744 and 746 at the upper and lower ends of this chamber serve to confine the wax within the chamber while permitting passage of the thread therethrough. The conduit 740 opens at its upper end into the chamber 706 formed in the bracket 708.

With this construction and arrangement of the thread waxing device, a continuously available supply of wax is provided which, because of the circulatory system above described, is maintained at all times in a fresh and usable condition. The construction shown has the specific advantage that the wax and the thread are both brought to a point close to the work without being exposed to the air stream created by the chip blower. The applying of the wax to the thread as it passes through the looper nose has been found to be of substantial advantage in that the wax on the thread does not have an opportunity to dry off or set before the stitch is formed and finally set in the work.

The invention having been described, what is claimed is:

1. In an inseam shoe sewing machine adapted for sewing a chain stitch, the combination of a hook needle, a looper provided with a thread eye movable to position a bite of thread in the needle hook when projected through the work, a thread finger cooperating with the looper to engage said bite of thread in the needle hook,

a thread take-up for drawing the thread passing through the looper to the needle and work, and a waxing device for the thread comprising a wax pot, an applicator located at the looper thread eye for supplying wax to the thread, and a closed conduit extending from the pot to said applicator for supplying wax to the thread only at said looper thread eye.

2. In a chain stitch wax thread shoe sewing machine, the combination with stitch forming devices including a hook needle and a needle threading looper, and devices guiding the thread from the supply to said looper while unwaxed, of a waxing device comprising a wax applicator on the looper for applying wax to a portion of said unwaxed thread passing through the looper, and means for supplying wax under pressure to said applicator.

3. In a chain stitch wax thread shoe sewing machine, the combination with stitch forming devices including a curved hook needle and a needle threading looper formed with a thread eye through which the thread passes, of a thread waxing device comprising means on the looper supplying wax at the thread eye and applying said wax to the portion of said thread passing through said thread eye, said means including a conduit for conducting wax to said thread waxing device.

4. In a chain stitch wax thread shoe sewing machine, the combination with stitch forming devices including a curved hook needle and a needle threading looper formed with a thread eye through which the thread passes, of a thread waxing device which comprises a wax pot for the storage of liquid wax, wax conveying conduits extending between the pot and the looper eye, and a wax receiving chamber in the looper eye connected with said conduits and apertured for guiding the thread through said chamber for the application of the wax to the thread.

5. In a wax thread shoe sewing machine having stitch forming devices including a hooked needle and a needle threading device, the combination of a thread waxing device which comprises a wax pot for the storage of liquid wax, a circulatory conduit system through which wax circulates from the wax pot and is returned thereto, means for maintaining a flow of wax through said system, a wax applicator on the needle threading device, and a conduit between the circulatory conduit system and the applicator through which wax is applied to the applicator.

6. In a wax thread shoe sewing machine having 45 stitch forming devices including a curved hooked needle, and a looper assembly comprising a looper rock shaft, an offset looper arm on the rock shaft, and a looper eye formed in the looper arm, the combination of a thread

waxing device which comprises a wax pot for the storage of cold liquid wax, a circulatory conduit system through which wax circulates from the wax pot and is returned thereto, means for maintaining a flow of wax through said system, a wax applicator in the looper eye, and a conduit formed in said rock shaft connected between said circulatory conduit system and applicator and through which wax is supplied to said applicator.

7. In a wax thread shoe sewing machine having stitch forming devices including a curved hook needle, a looper assembly comprising a hollow looper rock shaft disposed substantially in line with the tip of the needle when through the work, an offset looper arm on the rock shaft, and a looper eye formed in the looper arm, means 10 for guiding the feeding thread through said hollow rock shaft to the looper eye, a thread waxing device which comprises a wax pot for the storage of cold liquid wax, a circulatory conduit system through which wax circulates from the wax pot and is returned thereto, a reciprocating pump operable for periodically forcing wax through said circulatory conduit system, a wax applicator in the looper eye, and a conduit formed in said rock shaft connected between said circulatory conduit system and said wax applicator through which wax is applied to said applicator.

8. In a shoe machine of which the operating devices include a wax thread inseam sewing mechanism comprising a curved hook needle, a looper assembly having a hollow looper rock shaft disposed substantially in line with the tip of the needle when through the work, an offset needle threading looper eye with a wax applicator formed therein, and means for guiding the feeding thread through the hollow rock shaft to said applicator, an inseam trimming mechanism comprising a rotary tubular inseam trimming knife arranged to cause the knife edge to pass transversely across and to trim that portion of the inseam held by the last-completed stitches of the seam, and a chip exhaust device including an exhaust conduit through which chips are drawn off, and means including a separate wax conduit formed in said hollow looper rock shaft for supplying wax to the applicator.
